UNITED STATES PATENT OFFICE.

ROBERT E. PARROTT, OF LOS ANGELES, CALIFORNIA.

EXTENSION TABLE.

Application filed March 23, 1923. Serial No. 627,144.

This invention relates to extension tables, and more particularly to a table in which the extension leaves are permanently assembled with the remainder of the table structure, being adapted to be independently brought into position for use or to be housed out of the way beneath the main leaves of the table top when not required for use.

10 One of the objects of the present invention is to provide a novel means for storing the extension leaves of the table beneath the main leaves, in a compact manner and so that their presence will not be noticeable.

Another object of the invention is to provide a novel form of hinge by which the extension leaves are connected with the means provided for their storage, the hinge being 20 so constructed as to permit of the extension leaves being bodily shifted to assume the required positions when elevated for use or collapsed for storage.

Another object of the invention is to provide a novel form of hinge connection between the relatively foldable sections of each extension leaf, the connection being such that the leaf sections may lie in flat mutual contact when collapsed and stored away, 30 thereby occupying a minimum space, and will present a smooth upper surface when elevated to position for use so as to avoid the presence of any inequalities in the surface of the spread table.

25 In the accompanying drawings:—

Figure 1 is a plan view of an extension table embodying the invention, the extension leaves being adjusted to position for use;

40 Figure 2 is a detail vertical transverse sectional view on the line 2—2 of Figure 1 with the extension leaves in the position stated;

Figure 3 is a similar view illustrating 45 the extension leaves stored away;

Figure 4 is a perspective view of the storage tray for the extension leaves;

50 Figure 5 is a view similar to Figure 2 illustrating a modified form of the invention.

In that form of the invention shown in Figures 1 to 4, inclusive, the table is illustrated as comprising main leaves 1 which may be of any desired marginal contour and 55 which are fixedly secured to the upper sides

of side rails 2 and 3, the opposite sides of these rails being formed with longitudinal dove-tail channels 4 as best illustrated in Figures 2 and 3 of the drawings. The storage means for the extension leaves is in the nature of a tray indicated in general by the numeral 5 and comprising a bottom 6 which may be in the form of a sheet metal plate, and side rails 7 which may be of wood and which are provided upon their opposite faces with longitudinally extending dove-tail ribs 8 which fit in the grooves or channels 4, the rails 7 working slidably between the respective pairs of rails 2 and 3. The bottom 6 of the tray 5 is secured at its 60 lateral marginal portions to the under sides of the rails 7 and consequently occupies a plane spaced below the plane of the main leaves 1 of the table top so that between the said bottom 6 and the under sides of 65 the leaves 1 there is provided a storage space in which the extension leaves may be housed as shown in Figure 3 of the drawings, when they are not required for use.

Each extension leaf is indicated in general 70 by the numeral 9 and comprises two counterpart sections, indicated by the numeral 10. These sections at their meeting ends are formed with relatively narrow incisions 11 in which are received hinges 12 which serve 75 to hingedly or foldably connect the said sections 10. The hinges 12 are preferably of the form illustrated in the drawings and each comprises a link 13 of flat form provided with a longitudinally medially extending slot 14, the links preferably having 80 rounded ends 15 to permit of free pivotal movement of the parts. Pintle pins 16 are fixed in the leaf sections 10 and extend across the incisions 11 therein and through the slots 85 in the hinge links. The links 13 are of a width not greater than the thickness of the leaf sections 10 and are so pivotally engaged with the pintle pins 16 that their upper edges will lie flush with the upper surfaces 90 of the said leaf sections 10 when the leaf sections are in the elevated position shown in Figure 2 of the drawings, thereby providing a smooth and unbroken surface. Due to the character of the hinges 12, great freedom of movement of the leaf sections 10 is provided for so that these sections may with the greatest facility be swung about the hinges to lie flat upon each other in the manner shown in Figure 3 when the extension 105 110

leaves are to be stored away. The extension leaves and the main leaves will be provided with dowels 17 and sockets 18 so that when the extension leaves are elevated, the interfitting of these parts will serve to sustain the leaves in the elevated position.

In order that the extension leaves may be suitably connected with the storage tray 5 in a manner to insure of proper positioning 10 of the leaves when they are elevated for use or collapsed for storage and yet permit of their sliding movement when such adjustment is required, a hinge connection is provided between each extension leaf and the bottom 6 of the tray 5 and comprises a fixed hinge leaf 19 secured in any desired manner to the under side of one of the extension leaf sections 10 at the hinged inner end thereof, the leaf 19 being provided with a pintle 20 supporting a pintle pin 21. A second hinge leaf 22 is pivoted to the pintle pin 21 at one of its ends and at its other end is pivoted to an anchoring member 23 comprising a base portion 24 and a pintle 25, the said pintle 25 supporting a pintle pin 26 to which the lower or last mentioned end of the leaf 22 is, as stated, pivotally connected. The anchoring members 23 are slidably engaged in slots 27 formed in the bottom 6 of the tray 5, the said members 23 having shank portions 28 connecting their pintles 25 and bases 24 and these shank portions being received in the said slots as stated. In this manner the anchoring members are supported upon the bottom 6 of the tray for sliding movement thus permitting of shifting of the extension leaves. By reference to Figure 3 of the drawings it will be observed that when the extension leaves are not in actual use they may be stored away within the storage tray 5 by folding the sections 10 upon the hinge links 12 to assume a position lying flat one upon the other, the hinge leaf 22 being movable about the pintle pins 21 and 26 so as to permit of the lower section of the extension leaves, in this position of adjustment, overlying and resting upon the pintle 25 of the respective anchoring member 23. When either or both of the extension leaves is required for use, the sections comprising the same are swung and elevated to assume the position shown in Figure 2 of the drawings and the leaf is bodily slid toward one or the other of the main leaves of the table top.

In the previously described form of the invention the tray 5 and the extension leaf sections and their connections are all permanently built into the table structure, but in the form of the invention shown in Figure 5 the tray, the leaves, and the connections constitute in themselves a unitary structure which is attachable to any extension table, the sides of the tray which are in this instance indicated by the numeral 7,

being secured in any suitable manner as, for example, by screws 7^a, to the inner slides of the table.

It will be understood that if desired, the tray 5 comprising the bottom 6 and the side members by which it is supported, may be adapted to substantially any extension table by disposing the said tray with its said sides extending between the slides of the said table and with the tray resting upon or secured to the bridging which is fastened to the slide guide at either end. It will also be understood that the bottom of the tray may be of wood or of metal either as preferred.

Having thus described the invention, what is claimed as new is:—

1. In an extension table, the combination with the main leaves of the top, and the associated slides, of a supporting plate extending between the slides, an extension leaf comprising foldably connected sections disposable to rest upon the plate and also in position lying between the main leaves, and a hinge connected to one of said sections and connected with the supporting plate for sliding adjustment in a direction parallel to the slides.

2. In an extension table, the combination with the main leaves of the top, and the associated slides, of a supporting plate extending between the slides, an extension leaf comprising foldably connected sections disposable to rest upon the plate and also in position lying between the main leaves, and a hinge comprising a leaf pivotally connected at one end with one of said sections and a member connected with the supporting plate and to which the other end of the said leaf is pivotally connected, the said member being slidably adjustable along the plate in a direction parallel to the slides.

3. In an extension table, the combination with the main leaves of the top, and the associated slides, of a supporting plate extending between the slides, an extension leaf comprising foldably connected sections disposable to rest upon the plate and also in position lying between the main leaves, and a hinge comprising a member slidably mounted upon the said supporting plate and a leaf pivotally connected with the said member and with the connected end of one of said sections.

4. In an extension table, the combination with the main leaves of the top, and the associated slides, of a supporting plate extending between the slides and provided with a slot running parallel with the said slides, an extension leaf comprising foldably connected sections, a member slidably mounted in the said slot, and a hinge leaf hingedly connected with the said member and with one of said sections.

5. Table extension means comprising a

tray having a bottom and sides, the latter being adapted to be associated with the slides of an extension table, an extension leaf comprising foldably connected sections, 5 a member slidably mounted upon the bottom of the tray parallel to the sides of the tray, and a hinge leaf hingedly connected with the said member and with one of said sections.

10 6. In an extension table, the combination with the main leaves and the associated slides, of a plate disposed below the leaves and spaced therefrom and having a longitudinal slot paralleling the slides, an extension leaf comprising foldable sections, a member held to the plate and slidably in the longitudinal slot thereof, and a coupling pivotally connecting the said member to one of the extension leaf sections.

15 7. In an extension table, the combination

with the main leaves of the top, and the associated slides, of a sheet metal supporting plate extending between the slides and provided with a slot running parallel with the slides, an extension leaf comprising foldably connected sections, an anchoring member comprising an intermediate pintle portion engaging through the slot in the supporting plate and oppositely extending base portions lying beneath the under side of the 25 plate whereby the member is slidably supported by the plate and in the slot, and a member pivotally connected with the pintle portion of the last mentioned member and pivotally connected with the foldably connected end of one of the said extension leaf sections.

In testimony whereof I affix my signature.

ROBERT E. PARROTT. [L.s.]
